(57) CLAIM

The ornamental design for a game controller case, as shown and described.

DESCRIPTION

FIG. 1 is a front, bottom perspective view of a game controller case, showing my new design;

FIG. 2 is a front, top, right side perspective view thereof;

FIG. 3 is a front elevation view thereof;

FIG. 4 is a left side elevation view thereof; and,

FIG. 5 is a right side elevation view thereof.

The broken lines in the figures depict the portions of the game controller case that form no part of the claimed design.

1 Claim, 5 Drawing Sheets
